6 Claims. (Cl. 29—33)

The invention relates to a finishing road with a workpiece slide displaceable intermittently along a straight guide and with at least one machine tool bed located at every machining station perpendicularly to the road and adapted to receive one machining or processing unit.

The series production of industrial products has recently been changed in that manner that the separate machining of the workpieces in distinct shops, such as the milling, turning, planing, drilling shops and the like has been abandoned, and the production is carried out in optimum succession on a so-called finishing or transfer road. The machines, and mainly the machine tools are arranged along this road on either side thereof next to one another and equidistantly spaced. The resulting reduction in the transportation of the workpiece and the saving in the chucking times for the workpieces which need to be mounted only once led to a considerable acceleration and rationalisation of the entire manufacture.

However, these known finishing roads have the serious drawback that they are adapted only to receive one certain workpiece. Once the machines have been distributed, set and adjusted in their beds, a later change of the production to another or modified workpiece requires considerable expenditure for the new setting up and readjustment. Machine beds which had been set up in their foundations must be detached and the new machine beds must be aligned and embedded. In view of the many detachable connections between the workpiece clamped on the workpiece slide of the finishing road and the tool fixed in the machining part of the machine tool, this alignment is very extensive and can be carried out only by highly qualified labour.

Furthermore, the hydraulic system and the automatic electric circuits must also be adapted to this new programme of the unit. Also very often the mounting of the workpiece and its fixing no longer agrees with the requirements of the new workpiece to be machined so that structural changes must be made also in this respect, and the new arrangement must be tested.

In consequence of these drawbacks, finishing roads are nowadays only suitable for large series of uniform parts and desirable modifications have often to be abandoned, owing to the extensive and expensive rearrangement of the finishing road which would be necessary.

The present invention aims at eliminating these drawbacks and at providing a universal finishing road suitable also for smaller series, making possible a change in the production programme and in the machining units with their beds quickly and with a minimum of expenditure.

According to the invention, this object is realized in that the guide for the workpiece slide consists of longitudinal sections, each associated with one of the adjacent machines and comprising the necessary centering and clamping points for the slide, whilst all machine tool beds are located and easily detachably mounted on a profiled bar or the like, forming part of the finishing road.

The substantial advantage of this construction is that the individual centering and clamping points remain connected with the associated machine bed always in the same way so that a change in the production programme does not necessitate a new adjustment between the machine bed and the associated fixing point for the workpiece. In addition, the centering and fixing at all ma-

2

ching stations is effected only on the workpiece slide so that the centering and clamping can be effected without regard to the configuration of the workpiece itself. It is only necessary to align and mount the workpiece once before the start of the machining, as already known in the art.

In a preferred embodiment of the invention, each section of the guide is rigidly connected with a pair of machine beds with the such beds located on opposite sides of the guide, each such pair of machine beds being guided and located by means of two parallel profiled bars of the finishing road. This arrangement has also the further advantage that the individual machine beds no longer require special foundations on either side of the flowline. 10 According to the invention it is sufficient to bolt each bed or pair of beds to a support provided for this purpose which also carries the profiled bars or bars. Thus, these supports arranged side by side along the finishing road remain in their positions, and only the pairs of tools bolted thereto are exchanged for machines with the appropriate bed length according to the programme, so arranged that manufacturing programme can be carried out. Here it is important that this exchange requires no adjustment apart from the simple alignment of the beds in the axial 15 direction of the road, because the centering and clamping point associated therewith remains on the pair of machine beds itself.

According to a further feature of the invention, the successive supports of the finishing road are detachably 20 connected also in their lower zones. This results in an extraordinarily rigid bed for the entire installation which no longer requires special foundations. An existing finishing road may be easily shortened or extended if a new programme requires less or more operations than the 25 previous one.

Further features of the invention relate to other structural measures of the new finishing road which simplify and cheapen the manufacture and adjustment of the entire installation.

40 The invention will be further described, by way of example, with reference to the accompanying drawings, in which:

FIG. 1 shows the finishing road according to the invention in diagrammatic side elevation;

45 FIG. 2 is a cross-section of the road of FIG. 1 along the line II—II (showing only the parts visible along this cross-section, the road being slightly modified compared with FIG. 1);

FIG. 3 is a top view of the pair of machine beds shown 50 in FIG. 2 and of parts of the neighbouring machine bed pair;

FIG. 4 shows, on an enlarged scale, the connection of two adjacent machine tool beds of the road according to FIG. 1.

55 The production or finishing road of FIG. 1 consists substantially of similar upright supports 1, two profiled bars 2, located side-by-side in aligned grooves 1' in the supports in the longitudinal direction of the road and serving simultaneously for the alignment of these supports and a number of pairs of machine tool beds 3 which may be fitted on these profiled bars 2 by means of grooves 3' and connected by bolts with the supports 1. The first (starting) support and the last (finishing) support 1 have also special, similarly fixed machine beds 4 and 5; the machine bed 4 carries also a hydraulic installation, not shown in detail, for the workpiece advance, as explained in detail further below and an associated electrical control apparatus 6, whilst the machine tool bed 5 carries a shock-absorber 7, adapted to receive the workpiece (not shown) arriving at the end of the finishing road.

As may be seen more clearly from FIGS. 2 and 3,

each pair of machine beds 3 has two opposite machine beds 3a and 3b, between which there is located along the lateral centre plane of the pair of machine beds and thus along the vertical longitudinal centre plane of the road, a rigid guide for the workpiece slide 9, consisting of two guides 8. A vertically displaceable indexing pin 10 is mounted along the vertical centre lines of the guide and of the entire pair of machine beds, and two clamping jaws 11 are provided in the longitudinal direction of the pair of machine beds 3 in appropriate recesses of the two guides 8, so that they may be moved downwards from their normal position flush with the guides 8, in order to clamp the workpiece slide 9. In addition, each pair of machine beds 3, the length of which may differ in accordance with the requirements of the machining units (not shown) has lateral recesses 12 within the zone of the guides 8 which serve for the removal of the chips.

Each pair 3 of machine beds may be bolted together with the associated support 1 on both sides of the profiled bar 2 by means of screws or bolts 13. In addition, the successive supports 1 are detachably connected one to the other in their lower zones at the points 14 (FIG. 1) by means not shown in detail. Finally, the individual pairs 3 of machine beds are bolted together by connections 15, as shown in FIG. 4; these connections may be disconnected simply when a pair of beds has to be exchanged.

A horizontal conveyor chain 16 is located in lower recesses of the support 1, extending between the first and last support 1 and serving to return the workpiece slide 9, after the same has arrived at the end of the road and the workpiece has been detached therefrom. To enable the workpiece slide to carry out its circuit automatically, a space corresponding substantially to one processing station is left free between the first and second, and between the penultimate and last supports 1, bridged merely by the profiled bars 2 and at the bottom by the connections 17. Furthermore, the first support 1 is equipped with a carriage 19 vertically displaceable in a guide 18, and a similar vertical guide 20 with a further carriage 21 is located on the last support; these two carriages are vertically displaceable between their upper position (FIG. 1) and a lower position, in which guides 8a on these carriages and similar to the guides 8, are slightly below the upper run of the chain 16.

The hydraulic installation in the machine bed 4 serves also for supplying a forwarding cylinder 22 in which a forwarding piston (not shown) is displaceable by an amount corresponding to the length of one processing step in the direction of the movement of the workpiece slide. This hydraulic installation is also used for operating the indexing pins 10 and the clamping jaws 11 in accordance with the programming of the control device 6, through conduits provided in the machine beds 3 and through conduits 23 connecting the pairs of machine beds 3 (see FIG. 1) and through the connections 15 (see FIG. 4).

For operating the finishing roads, machining units (not shown) are mounted on the individual machine beds 3a and 3b by means of T-slots provided for this purpose, in such a manner that the required machining may be effected with the workpiece in its position. With this assembly, the correct relative position between workpiece and tool results from the integral connection between the machine bed and the centering and clamping device of the workpiece carriage 9. It is merely necessary to align the machining unit along the T-slots 25 in such a way that the desired machining, say, drilling, may be effected with the feed provided.

For carrying out other manipulations, requiring in addition to machining also other processing, such as heat treatment or quenching, the workpiece is first clamped on to a workpiece carriage or slide 9 and then placed with this slide on the carriage 19, located in its upper position. In addition, the successive positions in the direction of advance of the workpiece slide 9 are each occupied by an

empty workpiece slide until only the left carriage 21 in FIG. 1 remains unoccupied.

Then the whole installation is started up by switching on the control mechanism 6, causing the piston in the cylinder 22 to be advanced in the feed direction of the road by the length of one workpiece slide, that is to say, by the amount of one finishing step. The workpiece slide 9 carrying the first workpiece has now reached the first processing station whilst the empty workpiece slide, previously opposite the last station has now been moved into the carriage 21 and is held there by the shock absorber 7. This shock absorber forms simultaneously a stop by means of which the succeeding, abutting carriages 9 are held at their respective processing stations with sufficient accuracy. The exact alignment of the workpiece carriages 9 at the individual processing stations is effected by means of the indexing pins 10 which are moved by the control mechanism 6 and the hydraulic installation slightly towards the top and engage into conical bores (not shown) of the workpiece carriages 9, located above them. During the next control stage, the clamping jaws associated with each pair 3 of machine beds are moved downwardly and the centered carriage 9 is now firmly clamped against the guides 8 of the pair 3 of machine beds.

After this clamping, the control mechanism 6 issues a further impulse whereby the operation of the machining units located on the tool carriages 3a and 3b is initiated. During this processing a new workpiece slide 9 is fitted on the carriage 19 in front of the advancing piston which has now returned to its starting position and the empty slide 9 on the carriage 21 is lowered therewith on to the conveyor chain 16. When the work of all processing units along the road has been completed, this fact is communicated to the control device by a further impulse, causing first the clamping jaws of all working positions to be retracted and the indexing pins 10 to be lowered into their liberating position. Then the next step may be initiated.

During the following second advance movement of the advancing piston, the workpiece carrier 9 reaches the second processing stage, and the still empty workpiece carrier 9, now facing the last position is now placed on the carriage 21 which has meanwhile been returned to its top position and is again aligned by the shock absorber 7. The workpiece may now be processed by the second set of tools, after clamping and fixing the workpiece carriage again as described before. The workpiece may again be machined or processed from both sides and this action continues until it reaches, in its turn, with its carriage 9 the carriage 21. Here it is detached from the workpiece slide 9 during the machining of the next part and the empty workpiece carrier travels with the carriage 21 in a downward direction and is deposited on the conveyor chain; the conveyor chain transports this slide 9 again to the starting point where it is received by the carriage 19 which is now in its bottommost position. This carriage 19 lifts the empty workpiece carrier 9 to the top and the next workpiece is mounted, allowing the cycle to continue.

If the correct clamping of the workpiece should require more time than is available between the individual processing steps, the carriage 19 may naturally also be supplied from a separate clamping position for the workpieces (not shown) which receives the empty workpiece slides from the conveyor chain 16.

If a processing programme is to be changed, the required readjustments may be effected extraordinarily quickly. This change is effected merely by detaching the entire unit or the pair of units with the associated pair 3 of machine beds, forming together one or two independent machine tools, from the past station by slackening the bolts 13 and the connection 15, and moving it to the new position. Neither need a foundation be dismantled nor a support 1 be moved.

If it is desired, for example, to extend the finishing road, this may also be effected without extensive alterations. First, the individual pairs 3 of machine beds are dis-

mantled from the support 1 and the machine bed 5 with support 1 at the end of the finishing road is moved forward by an amount allowing a number of new supports 1—corresponding to the number of new processing stages to be fitted between the penultimate support 1 and the connection carrier 17 to the last remaining support. If the length of the hitherto used profiled bars 2 is insufficient, new and longer profile bars must be inserted. In addition, the conveyor chain 16 must be extended, but also this may be effected easily, say, by inserting additional links.

Then the new pairs of machine beds, corresponding to the altered programme, are bolted to their appropriate supports 1 and connected by the connections 15 with the hydraulic installation; when this is completed, the new, extended finishing road may be put into use with a larger number of workpiece carriers 9.

Although with presently used machining units a change of the working position requires also a further expenditure, connected with the displacement of the hydraulic installation and with the electrical connections to the power source or the like, it must be pointed out that also here new proposals facilitate and accelerate this change considerably. In this manner it is possible to carry out even extensive alterations of a finishing road without specialized labour and especially qualified electricians, for example, merely by means of electric sockets 26 provided on the supports 1 for connecting the same to the mains through a fuse box 27 and a main switch 28, even though, for example, the hydraulically controlled movements and the requirements of hydraulic fluid at the working position should change considerably.

Obviously, the invention is not restricted to the described finishing road in all its details. Thus, for example, every centering and clamping position could be associated with only one machine tool bed without thereby departing from the principle of the invention.

I claim:

1. An apparatus for facilitating the accurate progressive machining of a plurality of work pieces and for facilitating the substitution or addition of different machining operations, said apparatus comprising a plurality of upright supports disposed in spaced side-by-side relationship and detachably secured together, each support having a pair of spaced upwardly opening grooves, the grooves in all of said supports being in alignment, a pair of accurately machined bars disposed in said grooves with a portion

of each bar projecting above the upper surfaces of said supports, at least one machine tool bed secured to the upper surface of each support and disposed transversely of said bars, each bed having a pair of spaced downwardly opening grooves tightly receiving the projecting portions of said bars to accurately position each bed with respect to the adjacent bed, each bed serving to receive and support the machine tool to provide successive machining stations, a guide on each bed between said bars, said guides being in alignment, a plurality of work piece carriers slidably received on said guides, and means on each bed for centering and clamping a carrier for machining of a work piece carried thereby.

2. An apparatus as defined in claim 1 in which a pair of machine tool beds are secured to the upper surface of each support and disposed transversely of said bars, each pair of beds being accurately positioned by said bars, each pair of beds serving to receive and support a pair of machine tools disposed on opposite sides of said guide, each carrier serving to hold a work piece for machining by each pair of machine tools.

3. An apparatus as defined in claim 1 in which said centering and clamping means is hydraulically operated, each bed having passages for supplying pressure fluid to said centering and clamping means, and means for securing adjacent beds together, said last named means also providing communication between the passages in adjacent beds.

4. An apparatus as defined in claim 1 and including hydraulic means for intermittently advancing said carriers along said guides.

5. An apparatus as defined in claim 1 and including a shock absorber disposed adjacent the guide on the last bed for yieldably stopping movement of a carrier on said guides after completion of the last machining operation.

6. An apparatus as defined in claim 1 and including conveyor means for receiving a carrier after completion of the last machining operation and returning such carrier to the guide for the first machining operation.
